(57) **CLAIM**

The ornamental design for a beverage can lid, as shown and described.

DESCRIPTION

FIG. 1 is a front elevational view of the beverage can lid of the present invention;

FIG. 2 is a rear elevational view of the beverage can lid of FIG. 1;

FIG. 3 is a left side elevational view of the beverage can lid of FIG. 1, the right view being a mirror image thereof; and, FIG. 4 is a bottom plan view of the beverage can lid of FIG. 1, the top view being a mirror image thereof.

The broken line showing of a can in FIG 4 is for illustrative purposes only and forms no part of the claimed design.
